UNITED STATES PATENT OFFICE.

WILLIAM WEIR, OF CATHCART, SCOTLAND.

FEED-WATER-HEATING ARRANGEMENT ON STEAMSHIPS.

1,056,075.

Specification of Letters Patent. Patented Mar. 18, 1913.

Application filed February 10, 1912. Serial No. 676,859.

To all whom it may concern:

Be it known that I, WILLIAM WEIR, a subject of the King of Great Britain and Ireland, residing at Holm Foundry, Cathcart, in the county of Renfrew, Scotland, have invented certain new and useful Improvements in Feed-Water-Heating Arrangements on Steamships; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the heating of boiler feed water on steamships and is specially applicable in the case of steam-turbine-propelled vessels.

The invention consists in a novel arrangement and combination of machinery and apparatus which will be described in the following specification and more particularly set forth in the annexed claims.

In steamships in which the main propelling machinery is of the steam turbine type, the temperature of the condensed steam and water from the main condensers is usually lower than that in reciprocating-engined vessels on account of the higher vacuum carried in the former. In addition, the steam used by the auxiliary machinery in turbine-propelled steamships is generally large in amount and may be sufficient to raise the temperature of the feed water from the hot-well temperature to about 212 degrees Fahrenheit or even higher. The temperature range through which the feed water has to be raised is therefore greater than has heretofore been usual with reciprocating marine engines. Accordingly, if the feed heater is of the surface type, the amount of heating surface required is relatively large, and the heater is bulky and of considerable weight. When such feed heaters are fitted on the discharge side of the feed pumps, they are necessarily subject to the boiler pressure on the water side, i. e., the water side of the heating surface, and the water chambers are under the boiler pressure. With heaters, as generally designed, this involves large jointed surfaces subject to this high pressure, with attending difficulties. On the other

hand, any extensive degree of feed heating on the suction side of the feed pumps necessarily involves the placing of the feed heater in a relatively high position with respect to the feed pumps, in order that the suction of these pumps may not be impaired by the high temperature of the feed. It follows, accordingly, that some additional pump must be provided to force the water from the hotwell up into such a feed heater; and this involves complication and additional steam consumption.

According to this invention, I arrange a preliminary feed water heater of the direct-contact type on, or in close proximity to, the feed tank; and into this heater the main air pump delivers the water. In this feed heater the feed water mixes with a sufficient amount of auxiliary exhaust steam to heat the feed water to a temperature of approximately 140 degrees Fahrenheit, at which temperature the feed pumps will readily deal with the water without their suction powers being affected and without the necessity of receiving the water from an elevated position. The feed pumps then deliver the feed water at this temperature to a surface feed heater or heaters fitted on the feed pipe or pipes, wherein the feed water is raised in temperature to the limit imposed by the temperature of the heating steam which also is the auxiliary exhaust steam. To illustrate this, a hotwell temperature of 80 degrees Fahrenheit may be considered. The preliminary heating in the direct-contact heater may be to 140 degrees, and the final heating in the surface heater or heaters may be to 220 degrees. The total rise in temperature is thus 140 degrees, of which 60 degrees is carried out in the direct-contact or preliminary heater. It will therefore be obvious that the surface feed heater may be of greatly reduced dimensions, having only to heat the feed water 80 degrees instead of the full 140 degrees under existing arrangements.

In warships where the feed pumps are situated in each stokehold, the auxiliary exhaust main passes from the farthest stokehold through the others to the engine room where it joins the main auxiliary exhaust range. When surface feed water heaters are employed and are located in the stokeholds, it is common practice to carry a separate

100

105

auxiliary exhaust pipe from the engine room to these feed heaters; but, according to the present invention, I directly connect the feed pump, the fan engine, and any other auxiliary machinery, in each stokehold to the surface feed heater in that stokehold, and also fit a pipe from each feed heater to the present auxiliary exhaust line of pipe which extends from the engine room through all the stokeholds. The feed water is first heated in a direct-contact heater or heaters, as before mentioned, which is or are situated in the engine room, or in one or more of the engine rooms, and is then passed along the feed pipe to the stokeholds. In each stokehold the feed is further heated by the exhaust steam from the auxiliaries in that stokehold, any additional steam which is required being taken from the auxiliary exhaust line of pipe above referred to. No additional exhaust piping will be required between the stokeholds and the engine room. The steam for the direct-contact heater may be taken from the common auxiliary exhaust pipe, or, from any particular auxiliary engine, or group of auxiliaries, and may, if desired, be passed through an oil extractor before admission to the heater. I may, however, with advantage in certain cases select the source from which the steam is drawn for the direct-contact heater with a view to obtaining steam free, or relatively free, from oil.

Figure 1 of the accompanying drawings illustrate how my invention can be carried into effect in one convenient manner. Fig. 2 illustrates a modification. Both figures are diagrammatic.

Referring in the first place to Fig. 1, *a* is the bulkhead which separates the engine room, or one of the engine rooms, from the adjacent stokehold. *b* is a low pressure steam turbine which exhausts to a main condenser *c* from which the air and water of condensation are withdrawn by an air pump *d*, which will, as a rule, be of the independent steam-driven type. The air pump discharges the feed water through the filter *e* to the direct-contact heater *f* from which the water passes to the feed tank *g*. The air pump (if steam driven) exhausts by the pipe *h* into the auxiliary exhaust main *k* into which other steam driven auxiliaries in the engine room—not shown—may also exhaust. The heater *f* receives heating fluid from the auxiliary exhaust main by way of the pipe *j*. Connections are also provided between the auxiliary exhaust main and the auxiliary condenser *m*, and between the auxiliary exhaust main and the low pressure turbine *b*. The feed pipe *p* passes through the bulkhead *a* into the nearest stokehold and, when there are more than one stokehold, is continued through to the forwardmost or farthermost stokehold. In

each stokehold the feed pump *q* draws the partially heated water from the pipe *p* and pumps it through the surface feed heater *r* into the boiler or boilers *s*. The exhausts from the feed pump engine *t*, fan engine *u*, and any other auxiliaries in the stokehold, are led by the pipe *v* to the surface feed heater *r* and employed as the heating medium. A connection *w* is also provided between the surface feed heater and that portion *y* of the auxiliary exhaust main which passes from the engine room to the stokehold or stokeholds, so that the surface heater may obtain steam from the main when required.

The engine room auxiliaries, or a selection of the auxiliaries, may if desired be arranged to discharge their exhaust steam direct to the direct-contact heater instead of by way of the auxiliary exhaust main. Such an arrangement is shown in Fig. 2; some of the engine room auxiliaries are not connected to the auxiliary exhaust main *k* but discharge their exhaust steam, by way of the pipes *2*, *3*, *4*, and *5*, and through an oil extractor *x*, to the direct-contact heater *f* which, however, is also provided with a connection *j* to the auxiliary exhaust main. Otherwise the arrangement is the same as has just been described with reference to Fig. 1. It should be remarked that the auxiliaries which exhaust through the oil extractor direct to the direct-contact feed heater may also, if desired, be provided with direct connections to the auxiliary exhaust main. In the arrangement according to Fig. 2, the auxiliaries chosen to provide heating fluid for the direct-contact heater are preferably selected with a view to their exhaust containing the minimum of oil and, if desired, the oil extractor may be omitted.

In the arrangement according to Fig. 1 an oil extractor may, if desired, be provided on the pipe *j*.

By means of my invention, I obviate the necessity of two sets of auxiliary exhaust pipes from the stokeholds to the engine room and, even with the single exhaust pipe, if this should get damaged or require to be shut off, the feed can still be heated in each stokehold and delivered to the boilers at a high temperature.

Having now described my invention, what I claim as new and desire to secure by Letters Patent is:

1. In a steamship, in combination, a direct-contact feed heater located in engine room, means for supplying this heater with auxiliary exhaust steam, a condenser, a steam-driven air pump adapted to withdraw the condensed steam from said condenser and deliver it into said feed heater, a surface feed heater located in stokehold, a feed pump adapted to pump the feed water from said direct-contact heater.

to said surface heater, and means for supplying auxiliary exhaust steam to said surface heater.

2. In a steamship, in combination, a direct-contact feed heater located in engine room, an oil extractor located in engine room, means for supplying the said heater with auxiliary exhaust steam via said oil extractor, a condenser, a steam-driven air pump adapted to withdraw the condensed steam from said condenser and deliver it into said feed heater, a surface feed heater located in stokehold, a feed pump adapted to pump the feed water from said direct-contact heater to said surface heater, and means for supplying auxiliary exhaust steam to said surface heater.

3. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater, a surface feed heater located in stokehold, a feed pump adapted to pump the feed water discharged from said direct-contact heater to said surface heater, and means for supplying auxiliary exhaust steam to said surface heater.

4. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater, a surface feed heater located in stokehold, a feed pump adapted to pump the feed water discharged from said direct-contact heater to said surface heater, steam-driven auxiliaries in said stokehold, and pipe connections adapted to supply auxiliary exhaust steam to said surface heater from said auxiliaries in stokehold and from said auxiliary exhaust main.

5. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump

and from said other engine room auxiliaries to said exhaust main, a pipe adapted to convey exhaust steam from said exhaust main to said feed heater, a pipe adapted to convey exhaust steam from a selection of the engine room auxiliaries to said feed heater, a surface feed heater located in stokehold, a feed pump adapted to pump the feed water discharged from said direct-contact heater to said surface heater and means for supplying auxiliary exhaust steam to said surface heater.

6. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater, a pipe adapted to convey exhaust steam from a selection of the engine room auxiliaries to said feed heater via an oil extractor, a surface feed heater located in stokehold, a feed pump adapted to pump the feed water discharged from said direct-contact heater to said surface heater and means for supplying auxiliary exhaust steam to said surface heater.

7. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater, a pipe adapted to convey exhaust steam from a selection of the engine room auxiliaries to said feed heater, a surface feed heater located in stokehold, a feed pump adapted to pump the feed water discharged from said direct-contact heater to said surface heater, steam-driven auxiliaries in said stokehold, and pipe connections adapted to supply auxiliary exhaust steam to said surface heater from said auxiliaries in stokehold and from said auxiliary exhaust main.

8. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted

- ed to convey the exhaust from said air pump and from said other engine room auxiliaries to said exhaust main, a pipe adapted to convey exhaust steam from said exhaust main to said feed heater, a pipe adapted to convey exhaust steam from a selection of the engine room auxiliaries to said feed heater via an oil extractor, a surface feed heater located in stokehold, a feed pump adapted to pump the feed water discharged from said direct-contact heater to said surface heater, steam-driven auxiliaries in said stokehold, and pipe connections adapted to supply auxiliary exhaust steam to said surface heater from said auxiliaries in stokehold and from said auxiliary exhaust main.
9. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater via an oil extractor, a surface feed heater located in stokehold, a feed pump adapted to pump the feed water discharged from said direct-contact heater to said surface heater, steam-driven auxiliaries in said stokehold, and pipe connections adapted to supply auxiliary exhaust steam to said surface heater from said auxiliaries in stokehold and from said auxiliary exhaust main.
10. In a steamship, in combination, an auxiliary exhaust main, a direct-contact feed heater located in engine room, a condenser, a steam-driven air pump located in engine room and adapted to withdraw the condensed steam from said condenser and deliver it into said feed heater, other steam-driven engine room auxiliaries, pipes adapted to convey the exhaust from said air pump and from said other engine room auxiliaries to said exhaust main, a pipe adapted to convey exhaust steam from said exhaust main to said feed heater via an oil extractor, a surface feed heater located in stokehold, a feed pump adapted to pump the feed water discharged from said direct-contact heater to said surface heater, steam-driven auxiliaries in said stokehold, and pipe connections adapted to supply auxiliary exhaust steam to said surface heater from said auxiliaries in stokehold and from said auxiliary exhaust main.

In testimony whereof I have signed my name to this specification in the presence of two subscribing witnesses.

WILLIAM WEIR.

ROBERT MORRISON NEILSON,
GEO. H. FREEMAN.
